UNITED STATES PATENT OFFICE.

MARK ATLEE ERMOLD, OF HADDON HEIGHTS, NEW JERSEY.

PLAYING-CARDS.

1,212,198.

Specification of Letters Patent. Patented Jan. 16, 1917.

Application filed March 16, 1916. Serial No. 84,658.

To all whom it may concern:

Be it known that I, MARK ATLEE ERMOLD, a citizen of the United States, residing at Haddon Heights, in the county of Camden and State of New Jersey, have invented certain new and useful Improvements in Playing-Cards; and I do hereby declare the following to be a full, clear, and exact description of the invention, such as will enable others skilled in the art to which it appertains to make and use the same.

This invention relates to games, and more especially to those which are played with cards; and the object of the same is to produce a pack of playing cards with which a number of people (preferably more than three) may be amused or perhaps instructed while playing a game which has its debit and credit scores, hereinafter known as penalties and rewards. The basic principle of the game is that each player seeks as much reward and as little penalty as possible, and as these scores are always in numbers I prefer to print figures on the cards. As an instructive or amusing feature of the game, I propose also to print the cards with data additional to the numbers, and this data may be in the form of words or reading matter, illustrations, etc. The game as hereinafter described is based on the story of "Pollyanna," written by Eleanor H. Porter, and more particularly to the characters in said story; but I desire it distinctly understood that the game might be based on any other story, play, sketch, or musical or dramatic composition, and in fact the game in order to be instructive might be based on works of science, art, history, geography, etc.

The following specification may therefore be said to describe the preferred details of my pack of cards, as well as the preferred manner of playing the game therewith and reference is made to the accompanying drawings in which—

Figure 1 shows the various cards used in the game, and Fig. 2 is a perspective view of the "barrel" which stands on the table when the game is played as described below.

The cards themselves may be and probably will be of the size and texture used for ordinary playing cards, with ornamental backs not shown in the drawings, with square or rounded corners, and with or without the "squeezers" often used on playing cards and not shown herein because they form no part of the present invention.

The matter inscribed on the face of the cards is essentially figures or numbers, generally the names of characters from the story, etc., on which the game is based, and possibly other matter such as illustrations although I have not considered it necessary to go into the latter. This matter may be placed on the cards by printing, lithographing, or other suitable processes; and the number surely should be and the name probably will be duplicated and reversed at opposite ends of the card so that the latter may be played either end up. If there be an illustration, as shown in outline on the Pollyanna card in the drawings, this may be duplicated or not as preferred. The pack with which I have played my game is made up of ten groups containing six cards each, so that the pack has sixty cards in all, and the following description and the accompanying illustration are based on these figures although I would not be limited in this respect. All cards in each group are identical, and this fact cheapens the cost of production because the printer or lithographer need have but ten forms with which to print the faces of a pack of these cards. Also, if there are no illustrations the printing can be done in any ordinary office because it requires only the type necessary to produce numerals and names. On this understanding, and with a game based on the story of "Pollyanna," the cards are numbered and entitled respectively as follows: No. 1, Buffy; No. 2, Fluffy; No. 3, Ladies' Aider; No. 4, Mrs. Snow; No. 5, Nancy; No. 6, Jimmy Bean; No. 7, Dr. Chilton; No. 8, Aunt Polly; No. 9, John Pendleton; No. 10, Pollyanna.

By preference the last card named above and which bears the highest number and the title name of the story, is printed in red or in different shape or size of type so as to give it a certain characteristic of its own, additional to the fact that it bears the highest number. The card numbered 9 bears the name John Pendleton who, as is well known to those familiar with Pollyanna, was the grouch of the story, and this card I call the "grouch card" for purposes which will appear below. Also the vernacular preferably employed when the game is based on this story is as follows: The cards lying on the table are called the "garden," and alongside them stands the "barrel" as shown in Fig. 2 of the drawings. The dealer of the ordinary card game is in this case called the

"donor," and to deal or to play a card is to "donate" it. The cards are "freckles" which were the bane of Pollyanna's life. "Friend" is the name given to two or more cards when collected during the play, because the player is supposed to make a friend at that time; and "grouch" is the word facetiously applied to the donor who makes a misdeal or to a player who makes a misplay, as well as to the player who is forced to match the grouch freckle in the garden by the rules of play set forth below. If any player makes seven friends he is awarded a "rainbow," which is a special way of winning the game although he may not have secured the highest number of rewards. Each round of play is called a "prism," because it throws light on the character of hands held by the different players. Other special words from the story of "Pollyanna" might be selected and employed, or from other stories perhaps a larger number could be used. It is essential in any case, however, that at least one card, which is that bearing number 9 herein, shall be called the "grouch card" as seen below.

In playing this game, a donor is selected, and he shuffles the freckles and donates about half of the pack to the players and the garden, donating one each with its back up to the players and finally laying one with its face up in the garden. This he continues, around and around, until about half the pack is exhausted and the balance is placed in the barrel shown in Fig. 2. The players then sort their freckles, and he to the left of the donor attempts to match some of the freckles held in his hand with those lying in the garden—his best policy being to match the freckles with the highest reward number for a reason which will appear below. If he can make such a match he lays down his freckle upon the corresponding freckle in the garden and then takes in all of them bearing that number and name and turns them face down on the table in front of him. If this player is unable to make any such match, he donates one of his freckles, face up, to the garden, for the benefit of succeeding players—it being his best policy to eliminate the grouch freckle, or otherwise to get rid of a freckle bearing a small number. This is continued around to and including the donor, when a "prism" has been completed, and prisms are repeated until the freckles are exhausted from the players' hands. If at any time there are no freckles in the garden, the player in turn is obliged to donate one thereto, and at this time it is his best policy to donate the grouch freckle numbered 9, bearing the name John Pendleton. This is of course seen by other players, and interest in the game is immediately enhanced because of the danger to subsequent players who are compelled by

the rules to match with this freckle if they happen to have one remaining in their hand. When any player does so, he is said to make a grouch or become a grouch, and he suffers considerable derision which of course produces merriment and makes the game pleasing. The player making this match is now penalized by the score keeper, an amount previously agreed upon. If, on the other hand, any player should match with the last freckle remaining in the garden which is not labeled "John Pendleton," he announces "I'm glad I've made a friend," and takes up all the freckles as above described; and at this time is credited with a special reward by the score keeper to an amount previously agreed upon. These special rewards and penalties occur only when a match is made with a freckle which lies alone in the garden, but it will be found by experience that such exceptional occasions arise quite often in a game, and the imposition of penalties are of course the occasion of merriment. The donor now takes the freckles remaining in the barrel, and donates them again around and around as before until they are all exhausted; and if they do not come out even, the remaining freckles are laid in the garden alongside the others. Play is then resumed, and is carried out exactly as above; and the player making the last match is permitted to take in all the freckles remaining in the garden.

The counting is done in the following manner: Each player takes up the freckles which he has accumulated and which now lie face down in front of him, and announces his claim to the possession of a majority of freckles bearing the highest number possible. That is to say, assuming that he has three Pollyanna freckles out of the six there are in the pack, he claims to hold the majority on the assumption that the other three are scattered; and he substantiates this claim unless it is disputed. If it should so happen that some other player holds the other three, there is a tie and no score; but if his claim is substantiated he counts 10 if such was the number printed on these freckles, or he could count 9 if he held a majority of the John Pendleton freckles. This is continued for all players holding freckles above those numbered 5, and the remainder are considered too small to count. A second factor in counting is an arbitrary number (preferably 5 or 10 as agreed upon in advance) which is next awarded to the player who holds the greatest number of freckles. The score is kept by the selected person who adds these factors to the awards above mentioned "when a friend was made," and who deducts the penalties from time to time; and the game is won by that player whose score first reaches a number agreed upon in advance, as 100. An exception in the winning of the 130

game is that it is awarded forthwith to the first player who makes seven friends, which act constitutes a "rainbow." This means that the score keeper must keep a running account opposite each player's name of the friends he makes in the manner above described, and when this reaches seven it should be immediately announced by the score keeper, because it terminates both the prism playing and the game. It will not be necessary for the purpose of this specification to explain how the game might be used progressively, and in fact the idea is susceptible of amplifications and ramifications which need not also be gone into.

What I claim is:

A pack of cards for a game based on a story, said pack being made up of groups and the cards in each group bearing identical titles corresponding with the characters 20 in the story and differing from the titles on all other cards, the title on the cards in one group being the name of an unpleasant character in said story and indicating penalties, while those in the other groups indicate re- 25 wards.

In testimony whereof I affix my signature in presence of two witnesses.

MARK ATLEE ERMOLD.
